UNITED STATES PATENT OFFICE.

ROBERT L. PAULSON, OF BROOKLYN, NEW YORK.

SMOKE-UPTAKE.

1,108,222.

Specification of Letters Patent.

Patented Aug. 25, 1914.

Original application filed October 24, 1912, Serial No. 727,553. Divided and this application filed August 26, 1913. Serial No. 786,683.

To all whom it may concern:

Be it known that I, ROBERT L. PAULSON, a citizen of the United States, and resident of the borough of Brooklyn, in the county of 5 Kings and State of New York, have invented certain new and useful Improvements in Smoke-Uptakes, of which the following is a specification.

This invention relates particularly to a 10 smoke-pipe or uptake for self-leveling galley-stoves.

The subject matter hereinafter described is a division of an application filed by me on the 24th day of October, 1912, and bearing 15 the Serial No. 727,553. In the last named application I have claimed the general construction of the stove, whereas in the present application I direct my claims to novel compensating means for the differential movements of the smoke pipe and stove.

The object of the invention is to provide a simple and compact device for the purpose set forth, which can be easily manufactured as well as readily assembled or disconnected.

25 Further objects and advantages will become apparent as the description proceeds.

With the aforesaid objects in view the invention consists in the improvements and combinations of parts hereinafter described 30 in their preferred embodiments, illustrated on the drawings hereto annexed, and pointed out in the appended claims.

In the said drawings: Figure 1 is a front view of the uptake, a general outline of the 35 stove being shown; Fig. 2 is a vertical section of the uptake illustrated in Fig. 1, a portion of the stove being broken away; Fig. 3 is a fragmentary front view of a modified form of the invention; Fig. 4 is a horizontal section of the uptake, taken on the line 4—4 of Fig. 1; and Fig. 5 is a horizontal section of the uptake, taken on the line 5—5 of Fig. 2.

In these views the numeral "10" denotes 45 the galley-stove, which is hung on supports 11, 12 so as to be self-leveling irrespective of the rolling motion of the vessel. The smoke and gases of combustion pass out from the stove at 13.

50 A member 16 is fixed to the stove 10 over the smoke outlet 13 thereof. This member is hollow so as to constitute a continuation of the smoke-flue. It is formed with circularly curved sides 17 and straight or flat-

55 tened front and rear walls 18, 19. Basal

flanges 20 extend endwise from a lower neck portion 21 of the member 16, and bolts 22 passing through the flanges serve to fasten the said member in position on top of the stove. The upper part of this fixed or relatively stationary member is cut away as at 23, after the manner of a segment, on a line substantially parallel with the base. Pivot bolts 24 are threaded into the front and rear walls 18, 19, centrally with respect to the circularly curved sides or end walls 17. The bolts 24 terminate flush with the inner faces of the said walls 18, 19 of the stationary member 16 so as to avoid burning of the inner ends thereof and to afford an unobstructed passage for the flue-gases. Pivotally supported on the said bolts 24 is an upper movable member 30, constructed to take over the stationary member 16 on all four sides thereof. The said fixed member 75 stops short of the highest inside part of the movable member 30, and therefore the smoke can at all times find its way out through a neck 31 with which the upper portion of the latter member is provided, irrespective of the relatively different positions of the stationary member and the stove. The opposed outer side edges 32 of the said movable member 30, terminate on a diametral line 4—4 passing through the central bolts 24, so as to provide sufficient clearance with respect to the lower neck 21 of the said member. By virtue of the correspondingly shaped straight or flattened front and back walls on both the stationary as well as on the movable member, it becomes a comparatively easy matter to disconnect these parts by simply removing the pivot bolts 24. The upper neck 31 of the movable member 30 is surrounded by a sleeve 33, and the space included by the latter, the neck 31 and a bottom 34 joining them together constitutes an annular chamber 35 which forms the lower part of a slip or telescopic joint. The companion part of this joint is formed by the lower portion 40 of a smoke pipe 41, and the annular space or chamber in which the said end 40 operates may be filled with sand or other suitable packing material that will yield with the motion between the parts. 80 Caking of the sand around the end of the pipe is prevented by the heat of the gases from the flue passing through the connection.

At the proper height, on a level with the 110

smoke opening in the side partition or wall of the kitchen or galley, the said pipe 41 forms a right-angular extension or elbow 45. Adjacent to the place where the pipe 5 passes, the elbow is provided with a rim 46. A retaining flange 47 having a recess 48 for the reception of the said rim 46, holds the pipe in position while it permits oscillatory movement thereof. In order to facilitate 10 assembling of the parts, the flange 47 is split, or in other words, it is formed of two semi-circular parts which are held to the wall or other primary supports by bolts 49.

In the modification of the smoke-uptake 15 illustrated by Fig. 3, the coöperating stationary and movable members 16^a and 30^a respectively, are held in an inverted position. In this instance, the slip joint may be formed on the end of the pipe 41^a. This 20 construction can be advantageously employed when the exit for the smoke pipe passes vertically through the roof or ceiling of the galley instead of horizontally through the wall as indicated in Figs. 1 and 2.

25 While I have shown the preferred embodiment of my uptake connection it will be understood that numerous substitutions of equivalents can be made therein without departing from the spirit of the invention.

30 Having described my invention what I desire to secure by Letters Patent and claim is:

35 1. A compensating smoke-uptake for self-leveling stoves, comprising in combination with a stove, a smoke outlet having a pivotal connection with the latter, a telescopic joint above said connection, an elbow having a rim, and a retaining flange behind which said rim is free to rotate.

40 2. A compensating smoke-uptake for self-leveling stoves, comprising in combination with a stove and the smoke outlet thereof, a relatively stationary member having its lower portion secured to the top of the stove over its said outlet, a movable member pivoted concentrically to said stationary member and provided with an annular chamber, and a smoke pipe having its lower end in 45 telescopic engagement with said chamber.

3. A compensating smoke-uptake for self-leveling stoves, comprising in combination with a stove, a member fixed to the latter and having straight front and rear sides and curved ends, a semi-circular member taking over said fixed member and pivoted 55 to the straight sides thereof equidistantly

from its said ends, a neck extending from the top of said movable member, a sleeve spaced from the outside of said neck and providing an annular chamber therewith, and a smoke pipe having its lower end telescopically received in said annular chamber. 60

4. A compensating smoke-uptake for self-leveling stoves, comprising in combination with a stove, a member fixed to the latter and communicating with the flue thereof, 65 said member having flattened front and rear walls and curved ends, a correspondingly formed movable member adapted to take over the outside of said fixed member, bolts threaded into the flattened sides of said latter member on which the movable member is pivoted equidistantly from said curved ends, the upper part of said movable member being formed with an annular chamber, and a smoke-pipe having its lower end in telescopic engagement with said chamber and the other end free to follow the motions of the stove. 70 75

5. A compensating smoke-uptake for self-leveling stoves, comprising in combination with a stove, a hollow member fixed to the latter, a correspondingly formed movable member taking over said fixed member and pivoted concentrically thereto and provided with an annular chamber, a smoke-pipe having one end in telescopic engagement with said chamber and its other end formed with an angularly offset portion, and means for securing said portion rotatably in position on a primary support. 80 85 90

6. A compensating smoke-uptake for self-leveling stoves, comprising in combination with a stove a smoke outlet pivotally connected with the latter and provided with an annular chamber for packing material, a vertical smoke-pipe having its lower end slidably received in said chamber, the other end of said pipe extending horizontally, a rim on the horizontal end of said pipe, and a split retaining flange recessed to take over said rim, the same securing the pipe to a primary support while permitting oscillatory movement thereof. 100

Signed in the borough of Manhattan in the county of New York and State of New York this 22nd day of August A. D. 1913. 105
